OF COLEMAN, TEXAS, AND ONE-THIRD TO E. H. McDANIEL, OF HUBBARD, TEXAS.

RAIL-JOINT.

1,075,554.

Specification of Letters Patent.

Patented Oct. 14, 1913.

Application filed July 27, 1912. Serial No. 711,819.

To all whom it may concern:

Be it known that I, ALBERT C. ERNEST, citizen of the United States, residing at Hubbard, in the county of Hill and State of Texas, have invented certain new and useful Improvements in Rail-Joints, of which the following is a specification.

This invention relates to rail joints, and has for its object to provide a joint in which the use of bolts for securing the chairs to the rails to be joined will be obviated.

A further aim of the invention is to provide a rail joint in which the chairs may be readily detached from the rails without the use of tools.

The invention also contemplates the provision, in a device of this class, of chairs so constructed that the weight imposed upon the rails will serve to cause the chairs to more firmly grip the base flanges and webs of the rails to be connected.

In the drawings: Figure 1 is a perspective view of a rail joint embodying the present invention; Fig. 2 is a vertical transverse 25 sectional view therethrough and taken also through one of the ties supporting the joint; Fig. 3 is a horizontal sectional view on the line 3—3 of Fig. 2; Fig. 4 is a perspective view of one of the securing devices for the 30 chairs and rails.

In the drawings, the rails to be connected are indicated by the numeral 1 and are of the usual form except that each rail is formed adjacent its end which is joined to the other rail with a slot 2 extending transversely through the web 3 thereof directly below the tread 4. The base flanges of the rails are indicated at 5 and are of the ordinary form.

The ties upon which the rail chairs are to be supported are indicated by the numeral 6 and each tie has the upper surface of its supporting portion beveled downwardly in opposite directions, as indicated at 7. Thus the tie may be said to be provided with synclinal supporting surfaces.

The chairs forming the joint are of counterpart construction and each includes a base flange 8 having a plane horizontally disposed upper surface 9 and an inclined under surface 10, and each base flange 8 is formed near its outer edge with an upwardly and inwardly curved flange 11 terminating in an upstanding substantially vertically disposed flange 12. It will be observed that the flange 11 overhangs the

base flange 8 and that in assembling the chairs with the rails, the base flanges of the rails are fitted between the flanges 8 and 11 of the chairs with the chair flanges 12 engaging against the webs 3 of the rails. The 60 extreme outer edge of the base flange 8 of each chair is formed with notches 13 arranged to receive spikes 14 which are driven into the ties 6 for the purpose of holding the chairs in place.

By referring to Figs. 1 and 2 of the drawings, it will be observed that the inclination of the synclinal supporting surfaces of the tie 6 with respect to the upper surface of the intermediate portion of the tie is the same 65 as the inclination of the under sides of the flanges 8 with respect to their upper sides 9, so that, when the chairs, assembled with the rails to be connected, are disposed upon the ties the inclined under sides 10 of the chair 70 flanges 8 will rest upon the synclinal supporting surfaces of the ties. Consequently, any weight imposed upon the rails and their chairs will tend to cause the chairs to approach each other, thereby more firmly 75 clamping the webs and the base flanges of the rails.

By referring to Figs. 1, 2, and 3 of the drawings, it will be observed that the upper edge of the flange 12 of each rail chair is 80 formed with a notch 15 and that the side and bottom walls of these notches are beveled respectively, as at 16 and 17. As a means for holding the flanges 12 of the chairs securely to the webs of the rails, there 85 are provided blocks of the form shown in Fig. 4 of the drawings, each of these blocks being indicated by the numeral 18 and throughout its body portion having parallel upper and under sides and parallel side 90 faces 19. At each end, each block is formed with a head, the upper side of which is in the same plane as the upper side of the body portion of the block and the sides of each of these heads, indicated at 20, are beveled as 95 at 21, so that they merge into the side faces 19 of the body of the block. The heads 20 at their lower sides are beveled, as at 22, and their beveled faces merge into the under face of the said block. In other words, the 100 heads 20, except at their upper sides, are outwardly flared and their bevels correspond to the bevels 16 and 17 of the walls of the notches 15 in the upper edges of the flanges 12. In assembling the blocks with 105 110

the rails and chairs, the blocks are inserted through the slots 2 in the webs of the rails and the chairs are then assembled with the rails by disposing the upper edges of their flanges 12 against the rail webs below the slot and then moving these flanges up upon the webs until the walls of the notches 15 engage snugly with the heads of the blocks 18 in the manner shown in Figs. 2 and 3 of the drawings, whereupon the lower portions of the chairs are swung inwardly toward each other so as to cause their base flanges 8 to engage beneath the bases of the rails and their flanges 11 and 12 to bear flat against the upper sides of the base flanges and the side faces of the web 3.

From the foregoing description of the invention, it will be understood that there is provided a rail joint so constructed that the chairs may be readily applied to and disconnected from the rails and after application will be firmly held in place without the use of bolts or securing devices other than the blocks 18. It will also be apparent that the spikes 14 are relieved of strain to a considerable degree due to the fact that weight imposed upon the rails 1 will serve to cause the chairs, and especially their base portions, to move inwardly toward each other so as to more firmly grip the base flanges and webs of the rails.

What I claim is:

1. In a rail joint, rails to be joined, chairs disposed against the rails and having notches in their upper edges the walls of which notches are beveled, and a block carried by each rail and having beveled heads fitting in the openings in the chairs.

2. In a rail joint, rails to be joined, chairs disposed against the rails, the rails having each a slot and the chairs being formed with openings, the walls of which are beveled, and a block removably disposed in the slot of each rail and having beveled heads removably fitting in the openings in the chairs.

3. In a rail joint, rails to be joined, chairs disposed against the rails, the rails each having a slot extending beneath its tread and the chairs being formed in their upper edges with notches having beveled side and bottom walls, and a block disposed in the slot of each rail and having inwardly beveled heads fitting the notches in the chairs.

55 4. In a rail joint, rails to be joined, chairs

disposed against the rails and each including a flange resting against the web of the rails and formed in its upper edge with notches having beveled walls, each rail being formed with a slot in its web extending beneath its tread, and a block disposed in the slot of each rail and having a plane upper side extending beneath the bottom of the rail tread and provided at its ends with outwardly beveled heads fitting the notches in the flanges of the rail chairs.

5. In a rail joint, companion chairs having base flanges extending toward each other and having horizontally disposed upper faces for supporting the base flanges of the rails to be joined and having oppositely inclined under faces.

6. The combination with a tie having a supporting surface having synclinal faces, of companion rail chairs having base flanges the upper faces of which are located in the same horizontal plane and are arranged to support the base flanges of the rails to be joined, the under sides of the flanges of the chairs being inclined downwardly and inwardly whereby to seat within the concavity formed between the synclinal faces of the supporting surfaces of the tie.

7. In a rail joint, rails to be joined, chairs resting against the rails and each including a flange resting against the webs of the rails, the said flange of each chair being formed in its upper edge with notches having beveled side and bottom walls, each rail being formed with a slot in its web beneath its tread, and a block disposed in the slot in each rail, each of the said blocks having a plane upper surface resting against the underside of the tread of the rail, each block at its intermediate portion being decreased in width and thickness and having the lateral faces and under faces of its end portions beveled, whereby the block at each side of its intermediate portion will be of greater width and thickness than at its said intermediate portion, the said beveled faces of the blocks fitting the beveled walls of the notches in the flanges of the rail chairs.

In testimony whereof I affix my signature in presence of two witnesses.

ALBERT C. ERNEST. [L.S.]
